UNITED STATES PATENT OFFICE

FRANK M. AMOS, OF WHEELING, WEST VIRGINIA, ASSIGNOR TO WHEELING TILE COMPANY, OF WHEELING, WEST VIRGINIA, A CORPORATION OF WEST VIRGINIA.

INSULATOR.

1,376,307.

Specification of Letters Patent. Patented Apr. 26, 1921.

Application filed April 9, 1920. Serial No. 372,549.

To all whom it may concern:

Be it known that I, FRANK M. AMOS, a citizen of the United States, residing at Wheeling, in the county of Ohio and State 5 of West Virginia, have invented certain new and useful Improvements in Insulators, of which the following is a specification.

This invention pertains to insulators, and has reference more particularly to that type 10 wherein a base and cap piece are employed to hold and clamp one or more wires between them when the parts are secured together in binding or clamping relation to each other and to a support. Such base and 15 cap pieces are commonly made of porcelain and for many years past said elements when shipped from the factory were entirely disassociated and it was necessary for the workman to assemble them and secure them 20 in place by passing a nail or screw through the elements and into the member to which the insulator was to be attached. Of late years, however, several expedients have been proposed whereby the elements of the insulator could be assembled at the factory, 25 the arrangements being such as to allow a relative movement of the cap and base section so that the wire or wires could be readily placed prior to the final securing 30 act, while at the same time complete separation of the elements under ordinary usage and handling was precluded.

The present invention has to do with the latter type and has for its main object the 35 production of an insulator wherein but three elements are present, to-wit,—the base, the cap and the securing nail, the formation of the parts being such that a binding action between the nail and base will be automatically effected in the act of assembling the 40 elements at the factory, and this without the use or employment of any additional elements such as spring washers or sleeves, or the after treatment or deformation of 45 the nail to prevent the base being withdrawn therefrom. Moreover the necessary displacement or latitude of movement of the cap with reference to the base to admit of the positioning of the wire prior to final 50 placement of the insulator is provided for under the present arrangement.

The invention is illustrated in the annexed drawings wherein:

Figure 1 is a longitudinal sectional view 55 of the insulator;

Fig. 2 a transverse section on the line II—II of Fig. 1;

Fig. 3 a similar view on the line III—III of Fig. 1;

Fig. 4 a longitudinal sectional view of the 60 base the section being the same as that in Fig. 1 but with the nail removed; and

Fig. 5 a face view of the lower end of the base.

In the drawings 1 denotes the base and 2 65 the cap, the opposing faces whereof are provided with suitable wire engaging and clamping elements of any approved or suitable type; the construction shown being similar to that set forth and claimed in Letters 70 Patent No. 1,311,483, dated July 29, 1919. The cap and base are provided with alining bores to receive the fastening nail 3 and a yielding washer 4, preferably underlies the nail head and bears against the outer 75 face of the cap. The base 1 instead of being hollowed out at the bottom thereof, as is usually done, is, in the present instance hollowed out on one side of the center only, as at 5, leaving a thickened wall or body 6 80 opposite such recess. The bore 7 in the upper portion of the body 1 is axially disposed therein and alines with the bore in the cap. Said bore 7 at its lower end merges into a 85 groove or channel 8 formed in the adjacent face of the wall 6, said channel being inclined to the axis of bore 7 and inclining toward recess 5, as will be clearly seen upon reference to Figs. 1, 4 and 5. Furthermore, 90 the groove becomes gradually smaller or shallower toward its outer or lower end. Thus in making a factory assembly of the elements the nail 3 passes freely through cap 2 and into the bore 7 but when the nail 95 contacts the groove 8 it is deflected or bent to a slight extent, the nail being forced through the bore 8 and past and in contact with the deflecting groove until it assumes the position with reference to the base indicated in Fig. 1. This arrangement establishes such a direct frictional engagement 100 between the nail and groove that withdrawal of the nail is precluded except upon the application of considerable force and securely binds the base and nail together 105 while at the same time allowing the cap 2 to be moved freely upon the upper portion of the nail toward and from the base.

While the deflection and binding action 110 between the nail and the groove 8 is suffi-

cient to insure retention of the parts in their assembled condition, the deflection and friction are not sufficient to prevent the ready placement of the insulator in its final position and the driving of the nail home to bring the cap into binding relation to the wire or wires placed in the grooves in the outer face of the base.

It will thus be seen that I have produced a simple and effective insulator and one in which the parts are held in their factory assembled condition without the use of special securing means or elements or the necessity of any after treatment of any element employed, as, for instance the burring of the nail to prevent its withdrawal or separation from the base member after it is passed through the same. The fact that the wall 6 is thick and in effect forms an integral portion of the body of the base, precludes breakage of the body as the nail is forced through the base and deflected by the wall or channel formed therein.

What is claimed is:

25 1. In an insulator, the combination of a cap piece; a base, said base and cap having alining bores and said base also having an inclined face; a nail, said nail when passed through said bores contacting the inclined 30 face formed upon the base and making frictional contact therewith whereby the nail and base are normally held against separation.

2. In an insulator, the combination of a cap piece; a base, said base and cap having alining bores, and said base having a groove formed in the inner wall thereof, said groove lying in a plane inclined with reference to the bore in the base; and a nail, said nail when passed through the bores contacting the wall of the groove and being deflected thereby whereby the nail and base will be held against separation through friction established between the nail and base while the cap may be moved on the nail toward and from the base for the placement of the wire to be clamped.

3. In an insulator, the combination of a cap piece having a bore extending therethrough; a base piece having a recess formed in the bottom thereof and an oppositely disposed thickened wall, the upper portion of the base having a bore therein and the base likewise having an inclined groove formed in the inner exposed face of said thickened wall, said groove at its inner end alining with the adjacent portion of the wall of the bore in the base piece; and a nail passing

loosely through the bore in the cap and the bore in the base and making frictional contact with the groove as it is forced into contact with the wall thereof whereby the parts will be held against separation while still allowing relative movement of the cap on the nail toward and from the base. 65

4. In an insulator, the combination of a cap having a bore; a base piece having a recess formed in the lower portion of the body thereof with one wall of the recess lying in a plane in substantial coincidence with the axis of the body, said base having a bore formed therein and a groove in the wall aforesaid as an extension of the bore, said groove inclining at its outer end toward the longitudinal axis of the bore; and a nail 75 passing through the bores and making frictional contact with the groove.

5. In an insulator, the combination of a cap having a bore; a base piece having a recess formed in the lower portion of the body, said base piece having a bore in the upper part thereof and a tapering groove formed in the base as an extension of the bore; and a nail passing through the bores aforesaid and making a frictional binding 85 contact with the groove.

6. In an insulator, the combination of a cap having a bore; a base piece having a recess formed in the lower portion of the body, said base piece having a bore in the upper part thereof and a tapering inclined 90 groove formed in the base as an extension of the bore; and a nail passing through the bores aforesaid and making a frictional binding contact with the groove. 95

7. In an insulator, the combination of a cap piece; a base piece; and a nail, said base and cap being provided with alining bores to receive the nail, and said base being likewise provided with means formed integrally 100 therewith and located beyond the bore to frictionally engage the nail and to thereby hold the nail and base against separation.

8. As a new article of manufacture, an insulator base having a recess formed in the bottom thereof to one side of the center of the base, one wall of the recess standing in substantial vertical alinement with the axis of the base, said base having an axial bore formed therein and an inclined groove in 110 the wall aforesaid, said groove forming an extension of the bore and tapering toward its outer end.

In testimony whereof I have signed my name to this specification.

FRANK M. AMOS.
